AUTOMATIC REGULATOR SUITABLE FOR
FURNACE CONTROL

Weir C. Nurse, Omaha, Nebr.

Application September 12, 1935, Serial No. 40,206

3 Claims. (Cl. 236—102)

This invention relates to automatic regulators suitable for furnace control, and is herein illustrated as embodied in a thermostatic regulator for a hot air furnace.

Many forms of thermostatic regulators have been devised, and some of these may operate satisfactorily, but the devices are often complex, difficult to erect and adjust, and seldom working satisfactorily unless installed by expert workmen familiar with the special problems involved. Many devices depend upon closing electrical contacts which fail to work when dirty, and fail to work when the current is drawn from exhausted electrical batteries, and, moreover, can only be adjusted to "on" or "off" positions. Other devices may be simpler, but lack the desired adjustment for various temperatures or can be adjusted at only a limited number of points, or lack the possibility of remote control. Still others require to be installed by expert workmen when applied to furnaces which are already installed.

According to the present invention these and other difficulties are overcome, and a device is provided which is variably adjustable, at many points, capable of remote control, easily set up by a workman unskilled in the art, and rugged enough to withstand ordinary wear and tear.

Other features and advantages will hereinafter appear.

In the accompanying drawing,

Figure 1 is a diagrammatic side view of the device applied to a hot air furnace.

Figure 2 is a top view of the thermal element and its mount.

Figure 3 is a sectional side view of the same, showing some connecting parts, taken on the line 3—3 of Figure 2.

Figure 4 is an enlarged view on the line 4—4 of Figure 3.

Figure 5 is a similar view on the line 5—5 of Figure 3.

Figure 6 is an end view on the line 6—6 of Figure 3.

Figure 7 is an end view on the line 7—7 of Figure 3.

In the drawing a furnace 10 is shown as heating air entering by a duct, not shown, by means of a fire in the fire box within the usual top doors 11, 12, so that the hot air in the bonnet 13, may be conveyed by ducts, not shown, to rooms above the house floor 14.

The fire in the furnace 10 is shown as adapted to be controlled by the usual bottom draft door 54 or damper 15 and the usual hinged draft check

valve 16. The primary control is by the damper 15 which is shown as adapted to be automatically controlled, but the range of automatic control may be altered by a hand settable device 53 as described below.

For effecting this automatic control the bonnet 13 of the furnace is shown as crossed by a thermal controlling element 17, in the form of an iron tube or support 18 containing an aluminum bar or rod 19, the aluminum bar having a much greater coefficient of thermal expansion than the iron.

The aluminum bar 19 lengthens on being heated and therefore allows a regulating lever 20, on which it is pivoted at 21, to drop around 15 its floating pivot 22, with the result that the chain 23 drops and lowers the bottom draft door 15 to close or partly close it.

To obtain greater throw of the lever 20 by the aluminum bar 19, the bar is formed as a compound bar, having one stretch 24 looped around a pillar or pin 25 riveted diametrically across the tube 18 with its two ends 26 and 27 bent sharply around to the opposite sides of openings 28 in an iron connector element 29, and riveted 25 or headed over into the openings 28. Thus the aluminum bar 19 forms a U around the pillar 25. The iron connector element 29 is shown as a bar which may slide on the bottom of the tube 18 and connects the aluminum stretch 24 to a second aluminum stretch 30 which also is U shaped, being pivoted at its U 21, as mentioned above, and with its ends 31 and 32 bent sharply around, as seen at Figure 5, to pass through openings 33 in the connector element 29, above the bar 19 and far from the openings 28.

As is shown in Figures 2 and 3, the aluminum stretches 24 and 30 are each nearly the length of the tube 18, and overlap most of their lengths so that the effective length of the aluminum bar 19 is nearly double the length of the tube 18, thus increasing the throw of the regulating lever 20 in that proportion, minus, of course, any change in length of the iron connector element 29 in the opposite direction.

The pivot 22 of the regulating lever 20 is shown as the U bend 34 of a link 35 which passes through an opening 36 with beveled edges 37 in the lever. The link 35 also is bent into a U 38 at its opposite end which is similarly pivoted 40 in an opening 39 having beveled edges in an adjusting lever 40, said adjusting lever 40 swinging on a pivot 41 formed as the eye in the turned-over end of a threaded bolt 42. The threaded bolt 42 lies in the threaded center 43 of a milled 55

edged cap 44, turning in the end of the tube 18 and held in place by lugs or pins (not shown) which project into a peripheral groove 45 on the cap within the tube 18.

5 With a stretch of a little over four feet four inches between the pin 25 and the pivot 21, and with a connector element 29 which is almost four feet long it has been found possible to obtain sufficient throw of a four and a quarter-inch regulating lever 20, between centers, to operate the bottom damper 15 satisfactorily, and this also provides a range of thermal element operating temperatures from 70° F. to 390° F. in a throw of five inches of a five and three-sixteenth-inch adjusting lever 40. Automatic control is attained by movement of the compound bar 19 acting through the regulating lever 20 and chain 23 on the primary control damper 15. The adjusting lever 40 may be set at various positions to 10 provide a higher or lower range of automatically controlled temperatures.

In the form shown the adjusting lever 40 is adapted to be readjusted from more than one point, and the connections not only set the draft door 15 but also set the draft check valve 16. To this end the adjusting lever 40 is shown as adapted to be variously set by a chain or cord 46 connected to the outer end 47 of the lever and depending from the block 48 of a pulley 49.

25 30 The pulley 49 is adapted to be raised or lowered by the cord 50 which supports it and is shown as connected to the hinged check 16 at one end 51 and to an electric control motor at the other end 52. The cord 50 may be pulled up by rotating a control pulley 53 in an upper room above the floor 14. One point on the cord 50 is attached at the periphery of the pulley 53. Sufficient friction is provided in the pulley 53 to hold it at any setting against the weight or pull of the cord 50.

35 40 When the pulley 53 is rotated to turn to the right the point of the arrow on it, it lifts the check 16 by drawing on the cord 50 around its pulleys 54 and 55. At the same time the pulley 53 loosens the stretch of the cord 50 around the pulleys 56, 57, and 58, thus dropping the pulley 45 49 so that it drops the lever 40 and causes the lever 20 to drop and close or partly close the draft door 15.

45 50 The foregoing connections have been found useful although the door 15 works in one way manually and differently automatically.

In the form shown, the chain 23 is not connected directly to the lever 20, but is connected to a long narrow link 60 passing through an opening 61 in the end of the lever 20 and having bights 62 and 63 lying on opposite sides of the lever 40 so as to steady it.

The tube 18 is slotted at 64 on top to pass the lever 20, and the metal cut out of the slot is turned up into a stop 65 to prevent the tube 18 from slipping into the furnace bonnet 13.

The tube 18 is also slotted on the bottom at 5 66 to pass the lever 40, and the metal cut out of the slot 66 is turned down to form a second stop 67 to match the stop 65.

It will be seen that turning the milled head 44 screws the eye pivot 41 in or out of the tube 10 18, thus adjusting the normal setting of the bottom door 15 at will.

In addition to operating the door 15, the chain 23 may be connected to the throttle lever 68 of the valve 70 of the gas supply pipe 69 of a gas 15 fired boiler, the connection being such that the motion to close the door 15 partly closes valve 70.

Having thus described certain embodiments of the invention, what is claimed is:

1. In a temperature control, a thermally operated bar, a first lever to which said bar is pivoted, 20 a second lever for adjusting the first lever, a floating link on which both are pivoted, a second fixed pivot for the second lever, a controlled member, a link connecting said first lever to the 25 controlled member and embracing the second lever to guide it but allowing it to swing in its plane.

2. In a temperature control, a thermally operated bar, a first lever to which said bar is pivoted, 30 a second lever for adjusting the first lever, a floating link on which both are pivoted, a bar carrying a second fixed pivot for the second lever, a controlled member, a link connecting said first lever to the controlled member and embracing the second lever to guide it but allowing it to swing in its plane, a support, and a screw rotatable 35 on said support to adjust said bar to set the temperature at which the device is effective.

3. In a temperature control, a pair of U-bars 40 one above the other facing oppositely and overlapping through most of their length and expanding thermally at one rate, a connector lying between them and fast to the legs of each U and expanding thermally at another rate, a support 45 on which the connector may rest, a fixed member on the support to hold one U, an adjusting lever at the other end of the support, a pivot for the adjusting lever on the support, a regulating lever engaged by the other U, a floating link pivoted in both levers to form a fulcrum for the regulating lever, and a member operated by the regulating lever, a pulling device connected to each lever, and a link in the pulling device of one lever embracing the other lever. 50
